UNITED STATES PATENT OFFICE

PACIFIC J. THOMAS, OF WYOMING, PENNSYLVANIA, ASSIGNOR TO U. S. TEXTILE MACHINE COMPANY, OF SCRANTON, PENNSYLVANIA, A CORPORATION OF PENNSYLVANIA

HIGH SPEED REELING MACHINE

Application filed February 27, 1930. Serial No. 431,798.

This invention relates to an automatic reeling machine and particularly to a high speed skein winding machine adapted to wind a predetermined length of yarn in each 5 skein and then automatically stop.

Another object of the invention is to provide a high speed automatic reeling machine which may be used with a winding machine provided with the usual stop motion mechanism now in common use or with a special 10 mechanism, as preferred.

An additional object is to provide an automatic reeling machine wherein a plurality of skeins may be wound at one time, the structure 15 being such as to automatically stop the machine so that an accurate length on each skein is secured, the stopping mechanism co-acting with other stopping mechanism functioning when the yarn of any of the skeins 20 has been broken.

In the accompanying drawings,—

Figure 1 is a side view of a reeling machine disclosing an embodiment of the invention;

25 Figure 2 is an enlarged fragmentary sectional view, the counting wheel shown in Figure 1;

Figure 3 is an enlarged sectional view through Figure 1 on the line 3—3;

30 Figure 4 is an enlarged fragmentary sectional view through Figure 3 on the line 4—4;

Figure 5 is an enlarged elevation of the upper part of one end of the machine shown 35 in Figure 1, said view being taken from the direction indicated by the arrow "A" in Figure 3;

Figure 6 is a view similar to Figure 5 but looking at the parts from the opposite side, 40 certain portions being in section for better illustrating the construction;

Figure 7 is a view similar to Figure 3 but showing the parts in a different position;

45 Figure 7—*a* is a detail perspective view of a weighted catch or support and associated parts disclosing certain features of the invention;

Figure 8 is a view similar to the lower 50 part of Figure 7 but showing the parts in a different position;

Figure 9 is an enlarged fragmentary top plan view of the right-hand end of Figure 1.

In reeling machines designed to produce skeins different designs have been produced heretofore, whereby measured skeins have 55 been secured. In these prior machines difficulty was experienced in securing the desired speed and also in providing proper stop mechanism in case any of the yarns should break.

60 In the present instance a skeining machine has been provided which may be operated at high speed and yet practically determine or measure the amount of yarn wound on each skein. The machine embodying the present 65 invention will also automatically stop when one or more yarns break. The structure is such that this stoppage may be readily repaired and the machine again set in operation so as to finish the partly wound skeins, 70 after which the machine will automatically function for stopping the reel fly when the desired number of yards have been secured for each skein.

Referring to the accompanying drawings 75 by numerals, 1 indicates a frame of any suitable kind having desired uprights and cross bars forming a rigid structure for supporting the parts hereinafter fully described. As shown in Figure 1, the cross bar 2 supports a number of spools 3, and from these spools 3 the yarn 4 extends upwardly through suitable eyes 5 and 6 to the bars of a reel fly 7. These bars are connected by suitable spokes 8 with a central shaft 9 having end 10 journaled in a suitable socket in the shaft 11 and the opposite end removably journaled in a bearing socket 12 of any desired kind.

80 It will be noted from Figure 1 that a skein 90 13 is formed opposite each of the spools 3, and when the desired number of yards have been formed in each skein the mechanism is stopped, so that either a new fly 7 may be applied or the skeins removed and the yarns 95 4 connected to the fly for a second winding operation. The ends of the yarn 4 may be connected to the fly in any desired manner when starting the machine. In order to stop the fly 7 when the desired length of yarn has 100

been wound thereon from each spool a counting wheel 14 (Figure 7) is provided. This counting wheel is associated with certain other mechanism whereby the fly 7 will be 5 automatically stopped at the desired point. In addition to this counting wheel mechanism acting as an automatic stop, there is also provided automatic stop means shown at the left in Figures 3 and 7 for automatically 10 stopping the machine when any of the yarns 4 break. The counting wheel 14 and associated mechanism will be first described and then the automatic stop mechanism shown at the left in Figure 7 will be described. Wheel 15 14 is a worm gear and is adapted at different times to mesh with the worm 15. Gear wheel 14, as shown in Figure 2, is provided with a stop 16 rigidly secured thereto in any desired manner and with a drum 17 preferably 20 formed integral with the web of the wheel, though it may be made separately and rigidly secured in place. This drum accommodates the cable 18 which has one end secured to the drum and the other end secured to a weight 25 19. When wheel 14 is released from the worm 15 weight 19 will act to rotate the worm gear 14 back to its starting point with the stop 16 striking the stationary abutment 20. The abutment 20 is adapted to be mounted 30 on some part of the frame 1 and extend into the path of the stop 16. The wheel 14 is provided with an internally-threaded hub 21. An arm 22 is rigidly clamped to the exterior of hub 21 and extends downwardly so that 35 it will strike the pin 23 when in the plane of pin 23. This pin is adjustably mounted in the arm 24 and is clamped in the desired, adjusted position by set screw 25. Arm 24 is rigidly secured to the tubular bearing 26 40 and extending from this tubular bearing is a hook or catch 27 (Figure 7) adapted to interlock with the shoulder 28 of the collar 29 rigidly secured to the shaft 30. A stub shaft 31 (Figure 2) is screwed into the hub 21 and 45 is provided with an enlargement 32 which coacts with the nut 33 for rigidly clamping the shaft 31 to the link 34. In this way shaft 31 is held rigid and when the worm 15 rotates the gear wheel 14 away from abutment 20 the 50 gear wheel will gradually move over toward the plane of the pin 23 by reason of the action of the threads 35, and when the movement has been sufficient the lower end of arm 22 will strike pin 23 and swing this pin a short 55 distance or enough for catch 27 to be moved out of engagement with the shoulder 28, whereupon spring 36 which is under tension at this time will quickly move shaft 30 to the left in Figure 7. This action will cause 60 the sleeve 37 which is rigidly secured to shaft 30 to move from the position shown in Figure 7 to that shown in Figure 3. This sleeve carries a cam 38 having a stop 39. A supporting bar 40 is shown resting on cam 38 in 65 Figure 7, said supporting bar being rigidly secured at its upper end to link 34. When the cam moves from beneath the lower end of bar 40, as shown in Figure 3, link 34, counting wheel 14 and associated parts will drop down by gravity, so that the counting wheel will be out of mesh with the worm 15. As soon as these parts have been disengaged weight 19 and associated parts will begin to function to quickly rotate counting wheel 14 back to its starting position with the stop 16 in engagement with the abutment 20. While the counting wheel is being reset which only takes a few seconds the left-hand end of shaft 30 has functioned to operate certain other parts for stopping the reel fly 7. As indicated in Figure 7, shaft 30 strikes against the projection 41 on the weighted lever 42 which is pivotally mounted on shaft 43. The lever 42 is swung from the position shown in Figure 7 quickly over to the position shown in Figure 8, and when this occurs the pin or stub shaft 44 which is carried by the starting lever 45 is released, as the socket 44' on the arm 44'' is moved from beneath this pin. This will permit the starting lever 45 to drop downwardly under the action of gravity and force the brake 46 and link 47 and associated parts upwardly until the brake 46 is pressing against the wheel 7' with sufficient force to stop the rotation of reel 95 fly 7. It will be understood that wheel 7' is preferably a smooth friction wheel and the driving wheel 48 is also a friction wheel which is secured to the driving shaft 49. Driving shaft 49 may extend the full length of the frame 1, if desired, and is mounted in suitable bearings so that the driving pulley 50 may readily receive power from any suitable source. Preferably the driving wheel 48 is 100 rotating at all times and wheel 7' is stopped from time to time as the machine is operated. Starting lever 45 is provided with an integral extension 52 having a catch 53 adapted at certain times to fit into the notch 54 of the pivotally mounted pawl 55. The pawl 55 is pivotally mounted on the sleeve 29 and acts to hold the catch 53, link 47 and associated parts in a raised position. 105 The shaft 9 of the reel fly 7 may be removably secured to the shaft 11 in any suitable manner, as for instance, by having a rectangular end fitting into a rectangular socket. This will permit power to be transmitted from shaft 11 to shaft 9 and at the same time permit shaft 9 to be removed at 110 any time. Shaft 9 is supported on a swinging frame 56 mounted on a stub shaft 57 carried by the frame 1, as shown in Figure 9. Shaft 11 carries a pinion 58 meshing with the gear wheel 59 on shaft 60. Shaft 11 also carries a worm 61 meshing with the worm wheel 62 rigidly secured to the shaft 63 on which the worm 15 is mounted. From Figure 7 it will be noted that shaft 63 is carried by a sleeve 64 pivotally mounted at 65 on 115 120 125 130

the depending portion 66 of frame 56. A spring 67 acts to swing the worm 15 and associated parts downwardly as shown in Figure 7, while the adjustable stop 68 limits such swinging movement. By reason of the mechanism just described power is transmitted from shaft 11 to the counting wheel 14, but this power is naturally disconnected when the wheel 14 drops downwardly to the position shown in Figure 3. While power is being transmitted in this direction power is also being transmitted from shaft 60 through beveled gear 69 to beveled gear 70 secured to shaft 71. Shaft 71, as shown in Figures 4 and 5, carries an eccentric 72, and on this eccentric is mounted an eccentric band 73 having an extension 74 connected in any desired manner to the chain 75. As shaft 71 rotates the band 73 is given a back and forth movement, and consequently, the chain 75 is pulled in one direction and then released. This chain extends over an idler 76 and is connected to the arm 77 of lever 78. A spring 79' acts to resist any upward movement of arm 77, as shown in Figure 7 but by reason of the intermittent pulley movement on the chain 75 arm 77 and lever 78 are given a back and forth swinging movement, said lever and arm being preferably formed integral and mounted on the shaft 79. The lever 78 carries a bar 80 which ordinarily moves back and forth idly but when one of the yarns 4 breaks the particular eye 5 carrying that yarn will swing downwardly, as shown in Figure 3, and the supporting frame 81 will move the abutment 82 into the path of movement of the bar 80, whereupon the bar 80 will strike this abutment and move frame 82 so as to swing the levers 83. These levers are preferably integral with the sleeve 84 rigidly secured to shaft 43. By this movement shaft 43 is rocked, and as shaft 43 is rigidly secured to the arm 44' socket 44' will be moved from beneath the pin 44. This will allow the starting lever 45 to drop downwardly and consequently to force upwardly link 47 and brake 46 so as to stop the rotation of wheel 7' and the reel fly 7. After the thread has been tied and the eyes 5 restored to their former position, the machine may be started by grasping the handle 85 of lever 45 and raising the lever to the position shown in Figure 7. This will swing the parts from substantially the position shown in Figure 8 upwardly, as far as lever 45 is concerned, and downwardly, as far as brake 46 and associated parts are concerned. This will start the machine without having interfered with the counting wheel 14. The machine will then continue to function until the counting wheel 14 functions or until another yarn breaks. It will thus be seen that the breaking of the yarn does not interfere with the function of the counting wheel and consequently when the counting wheel functions

to stop the reel fly there will be the desired number of yards on each skein being wound.

As the machine functions shaft 71 will be rotated, and connected with this shaft is a crank 86 having a pin 87 extending into the slot 88 formed in the bracket 89. Bracket 89 is rigidly secured to bar 90 carrying eyes 6. As shaft 71 rotates motion is transmitted to bar 90 to cause the yarn to be laid properly in the skeins. This structure causes the bars to move back and forth within certain limits, and this movement is taking place while the reel fly is rotating. In connection with the counting wheel 14, it will be noted that the same is mounted on shaft 31, and this shaft is rigidly secured to the upper end of link 34. The lower end of link 34 is pivotally mounted on the stub shaft 91 secured to some part of the frame 1.

In operation the parts normally left in the position shown in Figure 3 when the machine is stopped. When in this position a new reel may be added, if desired, and the various yarns 4 connected therewith ready to be wound into skeins. After the yarns have been properly threaded through the various eyes and connected with the reel fly 7 the device may be started by pressing against the hand knob 92. This is connected to shaft 30 through a suitable rod and bracket 93, so that when this knob is pushed rod 30 will be moved to the right in Figure 3 against the action of spring 36. This movement is continued until the hook 27 snaps in back of shoulder 28 under the action of spring 27'. As the parts move to the position just described the cam 38 (Figure 7) will move beneath the bar 40 so as to raise link 34, counting wheel 14 and associated parts until they are in functioning position with the teeth of wheel 14 in mesh with worm 15. As the counting mechanism is set as just described pawl 55 will move from beneath the catch 53 and thus release the starting lever 45 which is then manually moved upwardly to the position shown in Figure 7. This will start the machine, provided power has been turned on to the shaft 49. It will be noted from Figures 3, 5 and 7 that spring 94 acts on arm 95 rigidly secured to sleeve 96 carried by a rod 97. Sleeve 96 carries one or more arms 98 which in turn carries a bar 99 functioning to prevent the various eyes from falling down too far when a yarn breaks. A stop bar 100 coacts with bar 99 to prevent the eyes 5 from swinging outwardly too far. Usually the stems of the eyes 5 are resting against bar 100, as shown in Figure 3, when the various yarns are properly moving through the eyes.

Ordinarily the starting lever 45 is used for starting the machine, but if desired, the treadle and rod mechanism 47' could be used, as the same is connected to extension 52. It will be understood that the starting lever 45 is pivotally mounted on a shaft 52' so that

the link 47 will receive the same motion whether lever 45 is actuated or treadle mechanism 47'.

What I claim is:—

- 5 1. In a reeling machine, a reel shaft provided with a reeling fly, a power shaft for driving said reel shaft, a counting wheel, a system of gearing for connecting the counting wheel with said reel shaft, cam means 70 for raising and holding the counting wheel in operative connection with said system of gearing, an arm movable with the counting wheel, and means actuated by said arm for moving said cam means to break the connection between the system of gearing and counting wheel, and a brake for stopping the movement of said reel shaft.
- 10 2. In a reeling machine, a reel shaft provided with a reel fly, a driving wheel connected with said shaft, a power wheel for operating said driving wheel, a counting wheel, an arm rigidly secured to the counting wheel, a system of gearing connecting said shaft to said counting wheel, means for raising and holding said counting wheel to a position in mesh with said system of gearing, means for releasing said raising and holding means, said counting wheel moving downwardly by the action of gravity away 80 from said gearing when released, and means set in operation by said arm for stopping the rotation of said reel shaft substantially at the time said counting wheel drops down under the action of gravity.
- 15 3. In a reeling machine, a reel shaft carrying a reel, a driven shaft for actuating said reel shaft, a driving shaft, contact wheels on said driven shaft and driving shaft, said contact wheels functioning to actuate said 85 reel shaft, a counting wheel actuated by said driven shaft, an arm movable with the counting wheel, means for supporting said counting wheel in operative position, a cam for holding said means in supporting position, a 90 spring for moving said cam to an inoperative position, and means actuated by said arm for releasing said cam.
- 20 4. In a reeling machine, a reel having a shaft, means for driving said shaft, a system of gearing operated by said shaft, a counting wheel, a swingable link supporting said counting wheel, a supporting bar for supporting said link so that the link will hold the counting wheel in mesh with said 95 system of gearing, a cam movable in one direction for supporting said supporting bar, a spring for moving said cam in the opposite direction, a catch normally holding said cam from moving under the action of said spring, 100 and a release arm carried by said counting wheel and positioned to engage said catch and move the same to inoperative position when the counting wheel has made the desired number of turns, whereby said spring 105 is allowed to function and said cam is moved 110

to permit said bar, link and counting wheel to move under the action of gravity in a direction away from said system of gearing.

5. In a reeling machine, a reel, a counting wheel, means for operatively connecting the counting wheel with the reel, whereby the reel will rotate the counting wheel, power means for driving said reel, means including a cam for holding said counting wheel in operative connection with said reel, a catch for holding said cam in operative position, a spring for moving the cam to an inoperative position, and means actuated by said counting wheel for releasing said catch.

6. In a reeling machine, a reel, means for driving said reel, a counting wheel, means for operatively connecting the counting wheel with the reel, so that the reel will drive the counting wheel, a shaft having a threaded end, said shaft being threaded into the hub of said counting wheel and supporting the counting wheel, a swinging link having one end rigidly secured to said shaft, a stop carried by said counting wheel, an abutment coacting with said stop for stopping said counting wheel at zero, an arm rigidly secured to the hub of said counting wheel, an adjustable stop positioned adjacent said counting wheel but on the opposite side to the stop carried by the counting wheel, said adjustable stop being in a plane parallel to the counting wheel, whereby when the counting wheel makes a certain number of revolutions it will be moved axially by reason of the threads on said shaft and will cause said arm to engage said adjustable stop and move the adjustable stop a predetermined distance, means including a cam for supporting the end of the link carrying said shaft, a spring for moving said cam away from said link, and a catch normally acting to prevent the functioning of said spring, said catch being rigidly connected with said adjustable stop so that when said stop is moved by said arm said catch will be released and said spring will function, whereby said cam and associated parts will be moved for releasing said link and permit the link and counting wheel to be moved downwardly under the action of gravity so as to disconnect the counting wheel from the means which normally connects the counting wheel with said reel.

7. A reeling machine, including a reel, means for rotating the reel, and a stop motion mechanism connected with said reel for stopping the rotation of the reel when any of the yarns being wound thereon are broken, said stop mechanism including a brake member, a pivotally mounted lever connected with the brake member for swinging the brake member to an operative and inoperative position, means acting as a catch for normally holding said lever in such a position that the brake will be inoperative, and a rocking member connected with said reel and moved 120

thereby for forcing said catch structure to a disengaged position when any of said yarns become broken, whereupon said lever will move to a position for causing said brake to function.

8. A reeling machine, including a reel, power means for rotating said reel, said power means including a driving and driven wheel, a swinging brake adapted to be brought into engagement with said driven wheel for stopping the rotation thereof, a link for actuating said brake, a starting lever for actuating said link, means acting as a catch for normally holding the starting lever in such a position that the brake will be inoperative, a swinging guiding eye for each of the yarns wound on said reel, the yarns being wound on the reel holding the respective eyes in a given position, said eyes being adapted to swing to a second position when any of said yarns break, a rocking bar, a spring for moving said bar in one direction and a power member for moving the bar in the opposite direction, and means actuated by said reel for moving said power member, whereby when any of said yarns break the guiding eye thereof will swing to a second position into the path of movement of said bar and said bar will move the guiding eye and the means acting as a catch so as to release said lever, thus stopping the machine.

9. A reeling machine, including a reel having a shaft, power means for driving said shaft, a pinion secured to said shaft, a gear normally meshing with said pinion, a transmission shaft rigidly secured to said gear, a sleeve for supporting said transmission shaft, means for pivotally supporting said sleeve substantially centrally thereof, a spring urging said sleeve to swing in one direction, an adjustable stop for limiting said swinging movement, a pinion rigidly secured to said transmission shaft, a counting gear wheel, supporting means for normally holding said counting gear wheel in mesh with said last-mentioned pinion, means for releasing said supporting means whereby said counting gear wheel will move downwardly under the action of gravity and thereby be disengaged from said second-mentioned pinion, and stopping means acting to stop the rotation of said reel at substantially the moment that said counting gear wheel is disengaged from the second-mentioned pinion.

10. A reeling machine, including a reel, means for rotating said reel, a pinion connected with the reel, driving means, a gear wheel meshing with said pinion, a beveled gear connected with said gear wheel, a second beveled gear meshing with the first-mentioned beveled gear, a shaft rigidly secured to said second-mentioned beveled gear, a crank connected with said shaft, a pinion extending from said shaft, an eye bar, means for slidably

mounting said eye bar, a bracket secured to said eye bar having a slot, a pin extending from said crank into said slot whereby when said crank is rotated said eye bar will be reciprocated, a plurality of eye members carried by said eye bars, said eye members guiding the yarn as it is mounted on said reel, and a stop motion mechanism connected to the shaft carrying said crank for stopping said reel and associated parts when any of the yarns are broken.

11. A reeling machine, including a reel, power means for operating said reel, a brake for stopping the rotation of said reel, a link connected with said brake, a starting lever connected with said link and adapted to raise and lower the link for applying and throwing off said brake, a pin extending from said starting lever, catch means for normally engaging said pin for supporting the starting lever in a position for holding the brake out of operation, a reciprocating rod positioned at one end adjacent said catch mechanism, and a spring acting on said rod for moving the same in a direction for shifting said catch mechanism away from said pin in order to permit said starting lever to function in a manner to force said brake into braking position, and means normally holding said spring against functioning.

12. A reeling machine, including a reel on which skeins are wound, means for rotating said reel, a shaft connected with said reel so as to be rotated thereby, an eccentric member rigidly secured to said shaft, an eccentric strap surrounding said eccentric member, a flexible member connected with said strap, and stop motion mechanism actuated by said flexible member.
